ROTARY CAR DUMPER

Milton W. Clark, Rockville Centre, N.Y., assignor to The Anaconda Company, a corporation of Montana
Filed Mar. 22, 1961, Ser. No. 97,576
6 Claims. (Cl. 214—55)

This invention relates to rotary dumpers for unloading open railway cars and the like by revolving them into inverted position and, more particularly, to improved means for holding the car on a platen within the dumper during unloading and for realigning the platen both longitudinally and laterally after unloading.

Rotary car dumpers generally include a heavy frame or cradle within which a car-supporting platen is mounted. In the upright position of the cradle, movable tracks on the platen should be aligned with stationary yard tracks so that one or more cars can be rolled onto the platen. The car is then clamped in some manner against the rails and the heavy cradle is rotated until the car is substantially inverted and its contents fall into a hopper beneath the cradle. Upon rotation of the cradle back to upright position, the tracks should come into realignment so that the car can be moved off the platen onto the yard rails. In general, a rotary car dumper can be considered satisfactory if over long periods of time and without extensive maintenance it can repeat this cycle of operation and each time return to a properly aligned position.

One of the major causes of misalignment in conventional rotary dumpers is that the combined effect of the enormous loads on the cradle plus the impact stresses occurring during rotation of the cradle eventually strain the structure to the point where critical dimensional changes take place. For example, along a cradle length of many feet, it is not unusual for the platen tracks to become misaligned an inch or so relative to the yard tracks after the strain of many cycles of operation, and as a result the dumper may be rendered inoperative because of interference between the tracks or because the cars are derailed when rolled on or off the dumper. However, the particular structure of the new car dumper assures that it can withstand the weight of the cars. In addition, means are provided to minimize impact stresses during the cycle of operation and to isolate the stresses set up by the expanding suspension springs of the car so that they cannot compound the load and cause serious strain.

Another critical factor in car dumper failure is the dimensional changes which result from extensive temperature variations during operation. When added to the strains mentioned previously, these thermal dimensional changes can seriously disrupt the operation of the dumper, particularly in many mining areas where rotary dumpers for unloading ore cars are expected to function under rapid and extensive changes in temperatures. Several novel features have therefore been incorporated into the new dumper to compensate for such dimensional changes caused by temperature variations.

In addition to protect the dumper structure from damaging stresses and strains, the present invention also provides means for accurately positioning the car-supporting platen both longitudinally and laterally relative to the yard tracks at the completion of each unloading cycle. Thus, the platen is movable longitudinally and laterally relative to its cradle to be properly centered by the positioning means.

In accordance with the invention, a rotary car dumper is provided wherein a car is moved from stationary tracks to movable tracks normally aligned therewith on a platen supported within a rotatable cradle. The improved structure comprises a plurality of rockers supporting the platen

2

and pivoted on the cradle to permit longitudinal and lateral displacement of the platen relative to the cradle. A side bumper is included on the cradle against which the car rests upon lateral displacement of the platen during rotation of the cradle. Locking means are provided for holding the platen relative to the cradle after the car comes to rest against the bumper.

The improved structure also includes means for supporting the car upon rotation of the cradle. These means 10 comprise a plurality of clamping members and a plurality of bars supporting the clamping members and slidably mounted to move them between positions retracted from and in engagement with the car. A plurality of releasable locking devices are employed for holding the respective bars and clamping members substantially fixed relative to the cradle in the car-supporting position. Each of these locking devices includes a locking shoe in surface-to-surface engagement with its associated bar. A sprag member pivotally abuts the locking shoe to toggle the shoe into locking engagement with the bar when the car exerts a load on the bar. A linkage is also included for displacing this sprag member and releasing the bar.

A further feature of the improved structure is that it includes a stationary stop engageable with the platen upon 25 rotation of the cradle into upright position to laterally displace the platen on the rockers and realign the tracks. Also, repositioning means are included for longitudinally displacing the platen on the rockers to bring the movable tracks into proper longitudinal position upon rotation of the cradle into upright position.

There are several advantages which result from the improved means for supporting the car during rotation of the cradle. For example, each clamping member acts 30 independently so that positive clamping is assured even though there may be rocks or dirt lodged between one or more of the clamping members and the car. If such pieces of matter are dislodged during rotation of the cradle, automatic adjustments are made to urge the affected clamping member firmly against the car even in mid-rotation of the cradle. Also, each clamping member is, 35 individually gripped by its own locking device so that failure of one would not leave the car unsupported during rotation of the cradle. Each locking device is designed to rely upon the load exerted on the clamping members in 40 order to lock its associated clamping member relative to the cradle.

The locking means which hold the platen relative to the cradle after the car comes to rest against the bumper served to relieve the car from a considerable portion of 45 the stress exerted on it as the loaded car is rotated in the dumper. Otherwise, the weight of the platen compounded by certain spring forces would be supported entirely by the wheel flanges on the high side of the car about midway in its inversion. After the car has been 50 loaded and the cradle returns to upright position, the platen and car are moved laterally into realignment with the stationary tracks by means of the stop element which gently guides the platen into position during the last few degrees of rotation of the cradle. Therefore, during rotation before and after unloading, the platen is moved laterally back and forth without subjecting the structure to severe impact stresses which might otherwise cause critical dimensional strain.

By mounting the platen for longitudinal movement on 55 the rockers and by including the repositioning means for longitudinal displacement of the platen after unloading, assurance is provided that the movable tracks on the platen will not interfere with the stationary yard tracks. Also, this permits the platen to be locked in normal position relative to the pit walls so that reaction to starting and stopping is taken up by the concrete walls and not entirely by the cradle structure.

A preferred embodiment of the new car dumper is described below with reference to the accompanying drawings, wherein

FIG. 1 is an elevation partly broken away and in section of the new rotary car dumper;

FIG. 2 is a plan view partly broken away of the apparatus of FIG. 1;

FIG. 3 is a section taken along the line 3—3 of FIG. 1;

FIG. 4 is an enlarged fragmentary section taken along the line 4—4 of FIG. 3;

FIG. 5 is an enlarged fragmentary view partly in section of the rockers supporting one movable platen;

FIG. 6 is a fragmentary section taken along the line 6—6 of FIG. 5 and showing the longitudinal rockers;

FIG. 7 is a fragmentary section taken along the line 7—7 of FIG. 5;

FIG. 8 is a fragmentary section taken along the line 8—8 of FIG. 5 and showing the lateral rockers;

FIG. 9 is an enlarged fragmentary section taken along the line 9—9 of FIG. 1;

FIG. 10 is an enlarged fragmentary section of the platen brake means;

FIG. 11 is a fragmentary elevation of the means for longitudinally and laterally readjusting the position of one platen on its rockers;

FIG. 12 is a fragmentary section taken along the line 12—12 of FIG. 11;

FIG. 13 is an enlarged fragmentary section taken along the line 13—13 of FIG. 12;

FIG. 14 is an enlarged fragmentary section taken along the line 14—14 of FIG. 11;

FIG. 15 is a section taken along the line 15—15 of FIG. 1 and showing the car clamping means;

FIG. 16 is a fragmentary section taken along the line 16—16 of FIG. 15;

FIG. 17 is an enlarged fragmentary section taken along the line 17—17 of FIG. 16 and showing in detail the locking devices and their actuating means;

FIG. 18 is an enlarged fragmentary section taken along the line 18—18 of FIG. 17;

FIG. 19 is an enlarged fragmentary section taken along the line 19—19 of FIG. 17; and

FIGS. 20 through 25 are diagrammatic cross sections of the car dumper in various positions from the upright starting position to the fully unloaded position where the car is substantially inverted.

Referring first to FIGS. 1, 2, and 3, the new rotary car dumper is shown in an operative position within a pit 30. The bottom of the pit opens in the direction indicated at 31 and 32 into hoppers into which the material is to be dumped. Leading up to edge of the pit 30 at the left as seen in FIG. 1 is a yard track 33 along which the loaded cars are moved toward the dumper. At the opposite end of the pit, a second yard track 34 leads away from the pit to carry the empty cars after they have been unloaded.

As shown most clearly in FIG. 3, the dumper includes a base structure 35 which extends throughout the floor of the pit in line with the yard tracks 33 and 34. In the embodiment shown, two rotatable cradles, indicated generally at 36 and 37, are supported on the structure 35 to receive two loaded cars at one time. Each of the cradles 36 and 37 is rotatably supported on four heavy roller assemblies 38. Each roller assembly includes a large main axle 39 mounted on the structure 35. A beam 40 is rotatably mounted about the axle 39 and in turn supports two secondary axles 41 and 42. The secondary axles 41 and 42 rotatably support rollers 43 and 44 respectively which ride on a peripheral rail formed about one of two large circular end frames 45—46 and 47—48 on the respective cradles 36 and 37. Hence, each of the cradles is adapted to rotate independently on its four roller assemblies 38.

Driving means are included for rotating the cradles 36 and 37 as shown in FIGS. 2 and 3. They include a

large two-directional electric motor 50 mounted in the pit 30 and positively geared to a primary drive shaft 51 extending along side both cradles. At the opposite ends of the primary drive shaft 51, it is geared to secondary drive shafts 52 and 53 associated with the cradles 36 and 37 respectively. The secondary drive shaft 52 rotates winches 54 and 55 at its opposite ends and the secondary drive shaft 53 rotates winches 56 and 57 in a similar manner. Cables 58 and 59 extend from the winches 54 and 55 respectively about suitable grooves formed in the periphery of the circular end plates 45 and 46 of the cradle 36. Similarly, cables 60 and 61 extend from the winches 56 and 57 respectively about suitable grooves in the circular end plates 47 and 48 of the other cradle 37. By this construction, the motor 50 is adapted to rotate the winches and turn the two cradles 36 and 37 on the roller assemblies 38. If one cradle happens to lead the other during rotation, adverse stresses are not set up because both cradles are driven by their own secondary drive shaft. Maximum rotation of the two cradles is limited by stops 62 and 63 (FIG. 3) on each circular end plate of both cradles which are adapted to engage one of the rollers on the roller assemblies 38 when the cradles reach upright or inverted position.

In FIG. 3, a railway car 64 is shown in dotted lines on tracks 67 supported on a platen 68 within the cradle 36. Also, the cradle 37 includes tracks 65 mounted on a platen 66 to support another of the railway cars 64. In upright position, the tracks 65 and 67 should be aligned with one another and with the yard tracks 33 and 34 leading to and from the dumper. To permit such alignment, the platens 66 and 68 are movably supported on their cradles for both longitudinal and lateral displacement.

One unit of the new platen-supporting means is represented by the rocker assembly shown in FIGS. 5 through 8 which is one of several such assemblies supporting each platen in each cradle. Interconnecting the circular end plates 47 and 48 of the cradle 37 are a number of floor beams 70. Rotatably mounted on one of the beams 70 is a pair of rockers 71 and 72 having arcuate toothed portions in engagement with a rack gear 73 rigidly mounted on a carriage 74 extending laterally beneath the platen 66. The carriage 74 rotatably supports a pair of lateral rockers 75 and 76 having arcuate toothed portions in engagement with respective rack gears 77 and 78 mounted on the underside of the platen 68. By these means, the platen is adapted to move longitudinally with respect to the cradle on its rockers 71 and 72 and laterally on its rockers 75 and 76. There are several of these rocker assemblies along the length of each platen so that both platens are fully supported and yet can move independently of one another.

A line of compression springs 80 are biased between a portion of each cradle and each of the platens 66 and 68 such that they urge the platens laterally on their rockers 75 and 76 to the right as shown in FIG. 5. In the upright position of the cradles these springs 80 urge the tracks 65 and 67 into alignment with the yard tracks 33 and 34. Once the cradles begin to rotate, however, the springs 80 are free to move the platens 66 and 68 to the right as shown in FIGS. 3 and 5 until the car 64 on each platen rests against respective bumpers 81 on each of the cradles 36 and 37.

In order to reduce the stress on the cars 64, platen locking means are provided as shown in FIG. 5 and in detail in FIG. 10. One of these locking means is associated with each of the roller assemblies 38 supporting the respective cradles. Each locking means includes a pawl member 82 pivoted to its associated cradle immediately beneath the platen. This pawl member includes a pendulum arm and weight 83 extending at an angle relative to the pawl member such that the weight 83 holds the pawl member 82 away from the platen (as shown in FIG. 5) when the cradle is in upright position.

A rack member 84 is affixed to the underside of the platen adjacent the pawl member 82 but spaced therefrom when the cradle is upright. As the cradle rotates, the weight 83 depends substantially vertically and thus turns the pawl member about its pivotal mounting until it reaches the position shown in FIG. 10. The pawl member is then in positive engagement with the rack 84 on the platen. In this manner, the platen is locked with respect to the cradle in the early stages of rotation of the dumper and the weight of the platen plus the force of the springs 80 is taken from the wheel flanges on the high side of the car during rotation. When the cradle returns to upright position after the car has been unloaded, the weight 83 swings the pawl member out of engagement with the rack member 84 and the platen is unlocked.

Referring now to FIGS. 3 and 11 through 14, means are shown for automatically positioning the platens 66 and 68 such that their tracks 65 and 67 are longitudinally and laterally aligned with respect to one another and to the yard tracks 33 and 34. The lateral positioning means includes a stop 86 affixed to and extending outwardly from each end of the pit 30 adjacent the remote ends of the two platens 66 and 68. Depending from the respective platens adjacent the stops 86 are brackets 87 each of which has a roller 88 rotatably mounted at its lower end. When the cradles return to upright position after unloading, these rollers 88 engage the corresponding stops 86 well before the cradles reach full upright position. Consequently, further lateral movement of the platens is prevented by the stops and the platens therefore move laterally relative to their cradles and compress the springs 80.

By properly locating the rollers 88 on the platens and the stops 86 on the wall of the pit, both platens are urged gently into proper lateral alignment with one another and with the yard tracks 33 and 34 at the end of the unloading cycle. Conversely, at the beginning of the unloading cycle, the rollers 88 remain in engagement with their stop 86 during the first few degrees of the rotation of the cradles while the springs 80 expand and move the platens relative to the cradles toward the bumpers 81. This greatly reduces the impact of the cars 64 on the bumpers 81 since they approach at a relatively slow rate dependent upon the rate of rotation of the cradles.

At the remote ends of the two cradles 36 and 37 adjacent the yard tracks 33 and 34 respectively are longitudinal repositioning means as shown in FIGS. 12 and 14. That associated with the cradle 37 is described herein since the longitudinal repositioning means on the cradle 36 is exactly the same. Extending outwardly from the circular end plate 47 near its periphery is an arm 90 which comes into engagement with a roller 91 on a bell crank 92 during the last few degrees of rotation of the cradle 37 into upright position. The bell crank 92 is pivotally mounted on the floor of the pit 30. The limits of movement of the bell crank 92 are shown in FIG. 12 in solid and dotted lines. A portion 93 thereof drives a rod 94 to which it is pivoted and which extends upwardly to a point adjacent the yard tracks 34 and the end wall of the pit 30.

Near the upper end of the rod 94 and mounted on the pit wall is a positioning block 95 which is slidably relative to the wall on posts 96 (FIG. 14). Another block 97 is also slidably mounted on the posts 96 but is separated from the first block 95 by a heavy compression spring 98. Between the first block 95 and a stationary plate 99 affixed to the pit wall is a wedge member 100 which is affixed to the upper end of the rod 94. The tapered surface of the wedge member 100 is in surface-to-surface engagement with a correspondingly tapered surface of the block 95 so that when the rod 94 moves upwardly it forces the wedge member 100 between the plate 99 and block 95 and moves the block 95 toward the platen 67 of the cradle 37. A block 101 is mounted on the platen 67 to

be engaged by the block 97 after the spring 98 has been compressed and the block 97 is moved forward by the wedge member 100.

Hence, the arm 90 on the cradle 37 actuates the rocker arm 92 during the last few degrees of rotation of the cradle 37 and thereby forces the wedge member 100 upwardly to bring the block 97 into resilient engagement with the block 101 on the platen. This causes the platen 67 to be longitudinally displaced a limited amount on its rockers 71 and 72. By these means, each of the platens 66 and 68 is moved inwardly toward the center of the pit 30 during the last few degrees of rotation of the cradles 36 and 37. This prevents the tracks 65 and 67 on the platens from interfering with the yard tracks 33 and 34 but spaces them closely relative thereto. It also prevents interference between the ends of the tracks 65 and 67 at the center of the dumper and establishes the most advantageous spacing at that point. In addition this mechanism locks the upright cradles relative to the pit so that the reaction of starting and stopping is absorbed by the pit walls and not the dumper structure.

Referring now to FIGS. 1 and 15 through 19, means are shown for supporting the car during rotation of the cradle. In FIG. 1, two car-supporting assemblies 103 and 104 are associated with the cradle 36 and similar assemblies 105 and 106 are associated with the cradle 37. Each of these assemblies is adapted to hold the car on both sides at one end thereof so that means are provided for holding each car at its four corners. Since the assemblies 103 through 106 are of identical construction they are described herein with reference only to the assembly 103 on the cradle 36, as shown in detail in FIGS. 15 and 19.

The assembly 103 includes two clamping members 108 and 109 on opposite sides of the cradle 36. These clamping members are mounted on respective bars 110 and 111 which at their upper ends include carriages 112 and 113 slidably mounted in suitable ways in the sides of the cradle structure. By these slidable mountings, the clamping members are adapted to move between positions retracted from (as shown in FIG. 15) and in supporting engagement with the car 64 within the cradle. The clamping member 109 extends rigidly from the associated carriage 113. As explained previously, the car 64 rests against the bumper 81 during rotation of the cradle and in doing so its upper edge extends beneath the clamping member 109.

Such lateral movement of the car 64 displaces it away from the opposite clamping member 108 and thus that clamping member must extend further out toward the center of the cradle to engage the other upper edge of the car 64. Since the clamping member 108 must extend far out when in clamping position, it might interfere with the locomotive or car as they move onto the cradle initially, and thus means are provided for withdrawing the large clamping member 108 away from the center of the cradle when it is in retracted position. Accordingly, the clamping member 108 is pivoted about a pin 115 on its associated bar carriage 112. An integral arm extends upwardly from the member 108 and supports a roller 116 at its outer end. Affixed to the cradle structure is a cam plate 117 which is disposed at an angle above the clamping member 108 to engage the roller 116 when the clamping member is moved upwardly into its retracted position. This causes the clamping member to pivot about a pin 115 and swing away from the center of the cradle into the position shown in FIG. 15. As the clamping member 108 is lowered by the bar 110 into car-supporting position, a roller 118 on the clamping member engages another cam plate 119 to swing the clamping member outwardly over the upper edge of the car.

Both bars 110 and 111 extend downwardly below the floor beams 70 of the cradle 36 and in the upright position 75 of the cradle are supported at their lower ends by pins

120 and 121 respectively. These pins are movable to allow the bars and clamping members to be lowered into car-supporting position. However, in order to urge the clamping members into car-supporting position without relying upon gravity, the bar carriages 112 and 113 are always urged in that direction by counterweights 122 and 123 respectively. (Advantageously, each counterweight may comprise two weights adapted to act together on their associated bar as shown in FIG. 1.) The counterweight 122 is supported by a cable 124 which is wrapped around pulleys 125 and 126 and is connected at 127 to the bar 110. Similarly, the counterweight 123 is supported by a cable 129 which is wrapped around pulleys 130 and 131 and is attached at 132 to the bar carriage 113. Each of these pulleys is rotatably mounted on the structure of the cradle 36. By these means, the clamping members 108 and 109 are urged toward car-supporting position notwithstanding the orientation of the cradle and the direction of gravitational forces.

The means for lowering the pins 120 and 121 and clamping members into car-supporting position are shown clearly in FIGS. 15 and 17. These include a cam roller 134 rotatably mounted in a stationary journal on a portion of the pit floor. A follower arm 135 is pivotally mounted about a pin 136 supported on a portion 137 of the cradle structure. At the end of the arm 135 remote from the pin 136 is a cam surface 138 which engages the cam roller 134 when the cradle 36 moves into upright position. During such engagement with the roller 134, the arm 135 is thereby forced into the solid line position shown in FIG. 17. During the initial degrees of rotation of the cradle 36, the arm 135 moves clear of the roller 134 and pivots into the dotted line position shown in FIG. 17.

The pin 120 supporting the bar 110 is mounted rigidly on the arm 135 so that when the arm moves off the roller 134 into the dotted line position in FIG. 17 the pin 120 moves with it and permits the clamping member 103 to be moved into car-supporting position by its counterweight 122. The other bar-supporting pin 121 is mounted rigidly on another arm 140 which is pivoted about a pin 141 on the structure of the cradle 36 and which is pivotally connected to the arm 135 by an intermediate link 142. By this construction, the arm 140 is drawn downwardly by the link 142 which moves with the arm 135 during the initial rotation of the cradle. Consequently, the arm 140 pivots into the dotted line position and thereby displaces the bar-supporting pin 121 and permits the other clamping members 109 to be moved into car-supporting position by its counterweight 123.

When the cradle 36 is substantially inverted, the weight of the car 64 is almost entirely supported by clamping members. Thus, releasable locking devices 144 and 145 are provided for locking the clamping members and their respective bars relative to the cradle. Each of these locking devices is supported substantially entirely by its associated bar but does not firmly lock its bar until after the clamping members have moved downwardly into engagement with the car. This is because there is a gap 146 between the frame of the locking device and the floor of the cradle. Consequently, the locking devices 144 and 145 are permitted limited movement relative to the cradle structure 36. This permits the car-supporting assemblies to compensate for the expansion of the suspension springs in the railway cars because the gap 146 is greater than the distance the wheel carriages are moved up by the springs when the car is inverted and unloaded.

Since the locking devices 144 and 145 are similar in construction, only the device 144 will be described. A backing shoe 149 is affixed to the frame of the locking device 144 and is in surface-to-surface engagement with the bar 110. Opposite the backing-shoe 149 is a movable locking shoe 150 which is also in surface-to-surface engagement with the bar 110. The locking shoe 150 is supported by a sprag member 151 which has a rounded

nose seated within a corresponding seat on the back-side of the locking shoe opposite the bar 110. At the end of the sprag member 151 opposite the locking-shoe 150 is a similar round nose which is seated within another corresponding seat in a plate 152 mounted rigidly with respect to the frame of the locking device 144. Provision may be made to place shims between the plate 152 and the frame of the locking device to maintain the sprag member 151 at its proper position relative to the bar 110.

- 5 10 A compression spring 153 is biased between an adjustable screw plate 154 (FIG. 18) in threaded engagement with the frame of the locking device. The spring 153 urges the sprag member 151 about its pivotal engagement with the plate 152 in a clockwise direction as seen in FIG. 17. However, the length of the sprag member 151 is slightly greater than the distance between the plate 152 and the locking shoe 150 so that the sprag member 15 15 can be forced by the spring 153 not further than the angled position shown in FIG. 17. Thus, the locking 20 shoe 150 is toggled against the bar 110. It is apparent that an upward force in the bar 110 as seen in FIG. 17 tends to wedge the locking shoe 150 tightly against the bar and also against the backing shoe 149 and thereby prevents the bar 110 from moving relative to the locking 25 device 144.

In order to release the locking device 144 an arm 155 projects rigidly from the sprag member 151 and is pivotally connected at its outer end to a rod 156. The opposite end of the rod 156 is pivotally connected to a bell-crank 157 which is pivoted about a pin 158 affixed to the cradle structure 36. Similarly, an arm on the sprag member of the other locking device 145 is pivotally connected to a second rod 159 which is pivotally attached to 157', the opposite end of the bell-crank 157. 35 By these means, rotation of the bell-crank 157 in a counter-clockwise direction as shown in FIG. 17 pivots the sprag member 151 downwardly against the force of the spring 153 and thus releases the locking shoe 150 from the backing shoe 149. This unlocks the rod 110.

- 40 The bell-crank 157 is turned in this manner by a yoke 160 keyed to the pin 158 and spanning arms 161 and 161' which extend rigidly from the bell-crank 157. The yoke 160 is attached integrally to a lever 162 which is actuated by a rod 163. Motion of the rod 163 to the 45 right as shown in FIG. 17 is resisted by a compression spring 164 which normally urges the bell-crank 157 into locked position. Hence, the rod 163 turns the yoke 160 through some degree of lost motion until the latter engages the arms 161 and 161' of the bell-crank 157. When 50 the bellcrank 157 turns, both the rods 156 and 159 move to open the locking devices.

At the opposite end of the rod 163, it is pivoted to a lever 165 which is rotatably mounted about a pin 166 affixed to the cradle structure. The other end of the lever 55 165 supports a roller 166 which is adapted to engage a cam plate 167 (FIG. 15) mounted on a portion of the pit floor. The configuration of the cam plate 167 is such that it deflects the lever 166 and holds the locking devices open during the initial stage of rotation of the cradle. 60 When the clamping members move into car-supporting position, however, the cam plate 167 is cleared by the roller 166 so that the compression springs 153 move the locking devices into locked condition.

- 65 The operation of the new rotary car dumper will be described with reference to all of the drawings but particularly to FIGS. 20 through 25 which show various positions of the cradle structure. Initially, the cradles 36 and 37 are upright and their tracks 65 and 67 are aligned with one another and with the yard tracks 33. Two loaded railway cars 64 are wheeled from the yard tracks 33 onto the dumper such that one car is supported on the cradle 36 and the other is supported on the cradle 37. During this initial movement of the cars onto the 70 75 dumper, the clamping member 108 is retracted as shown

in FIG. 15 so as not to interfere with the locomotive which may be used to move the cars.

No further preparation is required once the cars are on the cradle. Hence, the drive motor 50 may then be activated to rotate the primary and secondary drive shafts so that the winches 54-57 are operated to turn the cradles in a clockwise direction as seen in FIGS. 3 and 15. In the unlikely event that the cradles 36 and 37 begin to turn at an unequal rate such that one leads the other, serious torsional stresses are not transmitted through the drive means because each cradle is driven by its own secondary drive shaft.

In moving through the first few degrees of rotation from the position shown in FIG. 20 to that shown in FIG. 21, several operations are performed by the dumper mechanism. They will be described here with reference to the cradle 36 but it is to be understood that the operations are also performed on the other cradle. The very first movement of the cradle causes the compression springs 80 to move the platen 68 laterally on its lateral rockers 75 and 76 as the roller 88 on the bracket 87 remains in contact with the stationary stop 86. Thus, the car and platen move gently relative to the cradle at a rate determined by the rate of rotation of the cradle toward the bumper 81. This minimizes the shock which otherwise would occur when the car engages the bumper.

To further reduce the stress on the structure, the pawl member 82 swings relative to the rotating cradle structure until it positively engages the rack member 84. This occurs at substantially the same time the car reaches the bumper 81 so that some of the weight of the platen is absorbed by the pawl member. Thus, the pawl member serves to lend support to the wheel flanges of the car during the further stages of rotation.

During these initial stages of rotation, the clamping means are also operated as the car moves toward the bumper. The arm 135 rides off the cam roller 134 and moves the rollers 120 and 121 generally downwardly and away from the underside of the cradle floor. This permits both bars 110 and 111 which support the clamping members to be urged toward car-supporting position by the counterweights 122 and 123. As the clamping member 108 moves downward, its roller 116 travels along the plate 117 and then moves away from it so that the roller 118 on the plate 119 swings the clamping member about its axis 115 and into the extended car-supporting position.

While the clamping members are moved toward car-supporting position, the roller 166 on the lever 165 travels along the cam plate 167 to hold the locking device in open position. This allows the bars 110 and 111 to move toward car-supporting position as described. Once the car-supporting position has been reached, the roller 166 leaves the cam plate 167 so that the compression springs 153 acting on the sprag members 151 cause the locking devices to move into clamped position. Thus, the locked shoes 150 are toggled against the associated bars.

When these operations have been accomplished the dumping apparatus is in the position shown schematically in FIG. 21. In moving from the FIG. 21 position to that shown in FIG. 22, no further operations are performed except that more of the weight of the car is shifted to the bumper 81 and to the pawl member 82. It is to be noted that the position of the pulleys 125, 126, 130 and 131 is such that the clamping members continue to be urged toward car-supporting position by the counterweights 122 and 123 regardless of the orientation of the cradle. If any debris, such as dirt or rocks or the like, is lodged between a clamping member and the edge of the car and is later dislodged, the counterweights quickly displace the clamping member into car-supporting position and the rods 110 and 111 will slide through the unidirectional clamping devices 144 and 145.

After the dumper moves from the 90° position shown in FIG. 23 to the position shown in FIG. 24, a considerable proportion of the weight of the car is transferred

to the various clamping members. It is during this stage of rotation that the bars 110 and 111 pull the locking devices 144 and 145 against the cradle under the weight of the car to close the gaps 145 and 147 which had existed between the locking devices and the floor beams of the cradle. At about the same time, the weight of the car leaves its wheels so that its suspension springs tend to force the wheel carriages in what is now an upward direction. However, the expansion of the suspension springs cannot stress the cradle structure because the clamping members have moved away from the platen tracks a distance equal to the gaps 145 and 147 and this distance is great enough so that the wheels of the railway car are left slightly off the tracks.

The dumper proceeds to about the position shown in FIG. 25 where rotation is stopped by selective or automatic deactivation of the drive motor 50. The material contained in the car falls freely onto the hoppers 31 and 32 in the floor of the pit 30. It is to be noted that even in this position of the dumper, the counterweights 122 and 123 continue to urge the clamping members toward car-supporting position.

When the cars are unloaded, the motor 50 is activated in the opposite direction such that the cradle rotates in a counter-clockwise direction as shown in FIG. 15. Thus, the dumper passes through the position shown in FIGS. 24 and 23 and then the car settles once again onto the platen tracks. The counterweights 122 and 123 force the clamping members along with it so that the locking devices 144 and 145 again move away from the underside of the floor beams and reopen the gaps 146 and 147.

As the return motion continues from the FIG. 22 position back toward the position shown in FIG. 21, the various mechanisms again go into operation. First, the pawl member 82 leaves the rack member 84 to free the platen. The roller 166 on the lever 165 engages the cam plate 167 to rotate the bell-crank 157 in a direction such that it opens the locking devices which hold the clamping members. Also, the arm 135 engages the cam roller 134 to move both rollers 120 and 121 upwardly such that the clamping members are returned to retracted position. In such position, the clamping member 108 is deflected by the cam plate 117 into its withdrawn position.

During these last few degrees of rotation of the cradle, the longitudinal and lateral repositioning means go into operation. The roller 88 on the bracket 87 engages the stop 86 to prevent further lateral movement of the platen. The platen thus moves relative to its cradle against the compression springs 80 and swings gently into laterally aligned position. Also, the arm 90 on the cradle contacts the roller 91 on the bell-crank 92 and the wedge member 100 is forced upwardly between the plate 96 and the block 95. Since this wedging action occurs at the remote ends of both cradles, the two platens 66 and 68 are moved slowly toward one another. The platen rails thereby clear the ends of the yard tracks 33 and 34 as the dumper arrives at upright position and they are properly spaced and aligned relative to one another at the center of the apparatus. Such longitudinal and lateral repositioning of the platens provides assurance that the railway cars can be wheeled from one platen to the other and onto the yard tracks without risk of derailment even when severe temperature variations cause appreciable dimensional changes in the dumper structure.

65 I claim:

1. In a rotary car dumper wherein a car is moved onto a platen supported within a cradle which is rotatable on a base, means for supporting the car upon rotation of said cradle comprising a plurality of clamping members, a plurality of bars supporting the respective clamping members and slideably mounted to move them between positions retracted from and in supporting engagement with said car, a plurality of releasable locking devices for holding the respective bars and clamping members substantially fixed relative to said cradle in their car-support-

ing position, each of said locking devices including a locking shoe in surface-to-surface engagement with its associated bar, a sprag member pivotally abutting said shoe and said cradle to toggle said shoe into locking engagement with said bar when the car exerts a load on this bar, and linkage means for displacing said sprag member and releasing said bar.

2. A rotary car dumper according to claim 1 wherein each of said locking devices is supported by its associated bar in the upright position of said cradle and is movable with the bar to a limited extent relative to said cradle, and wherein abutting members are included on said cradle for supporting the respective locking devices and the bars affixed thereto during rotation of said cradle.

3. A rotary car dumper according to claim 1 which includes counterweight displacement means for forcibly urging each bar and clamping member toward car-supporting position, first cam means on said base, associated first follower means on said cradle in operative engagement with said linkage means, said first follower means being displaceable by said first cam means to unlock the locking devices when said cradle rotates from upright position, second cam means on said base, associated second follower means on said cradle engaging said bars, said second follower means being displaceable by said second cam means when said cradle rotates from upright position to permit said bars to be moved into car-supporting position by said counterweight displacement means, said first and second cam and follower means being adapted respectively to unlock said locking means and retract said bars and clamping members when said cradle returns to upright position.

4. A rotary car dumper according to claim 3 wherein the clamping members on one longitudinal side of said platen are pivotally mounted on their respective bars, cam plates mounted on said cradle in the path of travel of the respective pivotal clamping members, said plates being

adapted to be engaged by said pivotal clamping members and to pivot them away from the car when said bars move into retracted position.

5. In a rotary car dumper wherein a car is moved onto a platen supported within a rotatable cradle, means for supporting the car upon rotation of said cradle comprising a plurality of clamping members, a plurality of bars supporting the respective clamping members and slideably mounted to move them between positions retracted from and in supporting engagement with said car, a plurality of releasable locking devices for holding the respective bars and clamping members substantially fixed relative to said cradle in their car-supporting position, each of said locking devices comprising opposed locking and backing shoes in surface-to-surface engagement with opposite sides of the bar, a sprag member pivotally abutting said locking shoe and said cradle, spring means biasing said sprag member to urge said locking shoe forcibly against said bar, whereby in the inverted position of said cradle the load on said bars locks them between their respective sprag-actuated shoes, and linkage means operative against the force of said spring means for displacing said sprag member and releasing said bar.

6. A rotary car dumper according to claim 5 wherein each of said locking devices is supported by its associated bar in the upright position of said cradle and is movable with the bar to a limited extent relative to said cradle, and wherein abutting members are included on said cradle for supporting the respective locking devices and the bars affixed thereto during rotation of said cradle.
